PEG MOUNTABLE CLIP FOR HANGING ARTICLES THEREFROM

Burton Harrison, 43 Pinecroft Road,
Weston, Mass. 02193

Filed Oct. 17, 1969, Ser. No. 19,597

Term of patent 14 years

Int. Cl. D8—03

U.S. Cl. D8—259

FIG. 2

FIG. 3

FIG. 1 is a side elevational view of a peg mountable clip for hanging articles therefrom embodying my invention;

FIG. 2 is an end view looking from the left of FIG. 1; and

FIG. 3 is an end view looking from the right of FIG. 1. I claim:

The ornamental design for a peg mountable clip for hanging articles therefrom, as shown.
